panels 14 forming the sides of the container. Extending from the adjacent edges of the panels 13 and 14 are flaps 13^a and 14^a respectively, which serve to secure the panels 5 13 and 14 together when the latter are bent up to form the ends and sides of the container. In order to produce the container, the panels 13 and 14 are bent upwardly along the creases 11 until they assume, with 10 the central panel 12, a box-like form. The flaps 13^a and 14^a are bent outwardly along the creases 11, so as to extend diagonally outward from the corners of the container. In order conveniently to hold the ends 13 of 15 the container to the sides 14 during the packing operation, the flaps 13^a and 14^a may be secured together by means of rivets 15 (Fig. 2). By this means, a container is produced of box-like form, the upper end 20 being open ready to receive the goods which the completed shipping case is to contain. The shipping case which I have shown is particularly adapted for the shipping of cigar boxes or the like.

25 The cover is formed from a blank of a similar nature to the blank employed in the production of the container, although, of course, of somewhat larger dimensions; it comprises a top 16, ends 17, and sides 18, 30 the ends 17 and sides 18 being provided with flaps 17^a and 18^a respectively, similar to the flaps 13^a and 14^a of the container. When the container has been packed with the goods it is to receive, the cover is placed 35 over it, as shown in Fig. 2, the ends 17 and sides 18 being bent down over the ends 13 and sides 14 of the container, and the flaps 17^a and 18^a being bent outward so as to lie against the outwardly extending flaps 13^a 40 and 14^a. When the cover has been placed in position in this manner, rivets 19 are placed through the entire thickness of the flaps 18^a, 14^a, 13^a and 17^a, thereby securely fastening the cover to the container. It will be ob- 45 served that the case having been completed in this manner, both ends of each rivet are visible, so that it is impossible to remove a rivet without the fact of such removal having taken place showing clearly.

50 The embodiment of my invention, which I have shown in the drawings, includes a sealing cord; but, in some of the uses of my invention I may dispense with this cord. When the sealing cord is employed, means 55 for accommodating it are provided as follows: Formed in the flaps 13^a and 14^a of the container are holes 13^b and 14^b, and the flaps 17^a and 18^a of the cover are likewise formed with holes 17^b and 18^b. The holes 60 13^b, 14^b, 17^b and 18^b are so arranged that when the case is assembled, as shown in Fig. 3, all of these holes will coincide. When the cover has been placed upon the container and riveted in position to complete

the case, as described above, a cord 20 may 6 be passed through the holes in the outwardly extending flaps, the ends of the cord being brought together under a seal 21. A still further safeguard against unauthorized opening of the case is thus provided. 7 It will be seen that, both sides of the riveted flaps being accessible, the passing of the cord through the holes is a very simple matter and can be performed very quickly.

The case constructed in accordance with 7 my invention is very simple and durable, and it may be manufactured and put together at a low cost; moreover, once closed, it cannot be opened without a number of the rivets being removed, and if such rivets are 8 removed, they cannot be replaced without leaving evidences of the fact. Of course, if the sealing cord is employed, the case cannot be opened without breaking the cord or disturbing the seal. It is to be noted that I 8 have shown the ends and sides of the cover of such depth as to completely hide the ends and sides of the container; but this embodiment of my invention may be varied by 9 making the cover of a less depth than the 9 container. Moreover, it is not essential to secure together the ends and sides of the container by means of the rivets 15, as shown. If desired, the ends and sides of the container may simply be held in place 9 around the contents of the case by hand, and secured when the rivets 19 are placed through the flaps to fasten the cover to the container.

Having thus described my invention, 10 what I claim as new and desire to secure by Letters Patent, is:

1. A shipping case comprising a sheet of material having a center panel and four outer panels, the outer panels being bent up 10 to form the ends and sides of a container and being provided with securing flaps at the outer edges arranged to extend diagonally outward; a second sheet of material 11 having a center panel and four outer panels, the outer panels being bent up to form the ends and sides of a cover and being provided with securing flaps similar to the securing flaps of the container and adapted to lie adjacent thereto; and means 11 for finally securing the flaps of the container and the casing together, thereby to seal the case, for the purposes set forth.

2. A shipping case comprising a sheet of material having a center panel and four 12 outer panels, the outer panels being bent up to form the ends and sides of a container and being provided with securing flaps at the outer edges arranged to extend diagonally outward; a second sheet of material 12 having a center panel and four outer panels, the outer panels being bent up to form the ends and sides of a cover and being pro-

vided with securing flaps similar to the securing flaps of the container and adapted to lie adjacent thereto; means for finally securing the flaps of the container and the 5 casing together thereby to seal the case; and a sealing cord passing through the flaps of the container and the casing.

In witness whereof, I have hereunto subscribed my name in the presence of two witnesses.

KARL I. HERMAN.
